Property Law(57) **CLAIM**

I claim the ornamental design for a punch needle handle, as shown and described.

DESCRIPTION

FIG. 1 is a perspective view of a punch needle handle showing my new design;

FIG. 2 is a front view thereof;

FIG. 3 is a rear view thereof;

FIG. 4 is a side view thereof;

FIG. 5 is a second side view thereof;

FIG. 6 is a top view thereof;

FIG. 7 is a bottom view thereof; and,

FIG. 8 is a second perspective view thereof.

The broken lines depict environment that forms no part of the claimed design.
